UNITED STATES PATENT OFFICE.

JAMES J. COOPER, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

RAILWAY-CAR END CONSTRUCTION.

1,208,916.

Specification of Letters Patent. Patented Dec. 19, 1916.

Application filed June 1, 1914. Serial No. 842,082.

To all whom it may concern:

Be it known that I, JAMES J. COOPER, a citizen of the United States, residing at St. Louis, Missouri, have invented a certain 5 new and useful Improvement in Railway-Car End Construction, of which the following is a full, clear, and exact description, such as will enable others skilled in the art to which it appertains to make and use the same, reference being had to the accompanying drawings, forming part of this specification, in which—

Figure 1 is an elevational view of a car end of my improved construction. Fig. 2 is a vertical section taken approximately on the line 2—2 of Fig. 1. Fig. 3 is an enlarged horizontal section taken approximately on the line 3—3 of Fig. 1. Fig. 4 is a 15 enlarged detail section taken approximately on the line 4—4 of Fig. 1. Fig. 5 is a detail section similar to Fig. 4, and showing a modified construction. Fig. 6 is a horizontal section through the central portion of a modified form of the car end and 20 showing a transversely disposed trussed reinforcement therefor. Fig. 7 is an enlarged vertical section taken approximately on the line 7—7 of Fig. 6. Fig. 8 is a horizontal section similar to Fig. 6 and showing a modified 25 form of the horizontally disposed trussed reinforcement. Fig. 9 is an enlarged section taken approximately on the line 9—9 of Fig. 8.

My invention relates generally to railway 30 cars and more particularly to a pressed metal structure which forms the end wall of a car.

In railway cars, and particularly those 35 designed for and used in the transportation of freight, the end portions of the car body and the end walls are subjected to strains and stresses resulting from service shocks and vibrations and also by reason of the sudden starting and stopping of the cars, 40 and the shifting of the load and contents of the cars while the latter are in transit.

One of the principal objects of my invention 45 is to construct a car end from a plurality of sections of material, preferably sheet metal, either plain or corrugated, said sections being practically duplicates and arranged so that the joint between the sections

is horizontally disposed and in a plane approximately midway between the top and bottom of the end.

A further object of my invention is to 55 combine with the meeting edges of the two sections of which the end is formed, one or more joint members, preferably commercially rolled metal shapes, thereby providing 60 a comparatively simple, inexpensive car end which can be readily combined with an ordinary car underframe and superstructure, and which end by virtue of its transversely disposed reinforcement and its pressed ribs or 65 corrugations will be very effective in resisting such strains and stresses as may result from shifting loads, ordinary service shocks and vibrations or collisions.

A further object of my invention is to 70 construct a car end having a trussed reinforcement which extends transversely of said end, preferably at a point midway between its upper and lower edges, and which trussed reinforcement combines with the 75 meeting edges of the sections to form a water and dust proof joint, and at the same time providing a car end having a perfectly smooth inner face.

In order to comply with the Government 80 regulations relating to cars utilized for transportation of explosives, it is necessary to provide car ends which are entirely devoid of projections, such as rivet or bolt heads, on their interior faces, for, if such 85 construction were employed, it would be possible for a box or package of explosives when shifted suddenly within the car to strike against the projecting head of a bolt or rivet, and thus develop sufficient impact 90 to set off or effect a discharge of the explosives. Likewise it would be possible for a bolt or rivet when subjected to a blow from the exterior of the car to perform the functions of a hammer and transmit to a 95 box or package of explosives positioned against the inner face of the car end, sufficient impact to effect a discharge of said explosives.

With this consideration in view, it is one 100 of the objects of my invention to construct a car end having a substantially smooth flat inner face, which end is made up of two or more panels, the meeting edges of which

are joined in such a manner as that the rivets or bolts utilized in fastening the edges together are positioned so that it will be impossible for said rivets or bolts to transmit percussive blows to boxes or packages of explosives located immediately against the inner face of the car end.

With the foregoing and other objects in view, my invention consists in certain novel features of construction and arrangement of parts, hereinafter more fully described and claimed.

The car end illustrated in the accompanying drawings is made up of two sections or panels 10 and 11, the same being substantially duplicates and for this reason, it is possible to produce both sections or panels from one set of dies. The lower edge of the lower panel 10 is attached in any suitable manner to the underframe of a car, preferably the end sill thereof, and the side edges of said lower section are bent rearwardly as designated by 12, to form flanges which are adapted to be attached to parts of the superstructure, preferably the corner posts. The upper edges of the lower section 10 are bent outwardly into a horizontal plane so as to provide an attaching flange 13 which combines with a reinforcing joint member hereinafter described.

The body of the section 10 is preferably provided with a series of vertically disposed outwardly pressed ribs or corrugations 14, the ends of which terminate at or near the upper and lower edges of said lower section. These ribs or corrugations can be of the same width and depth throughout their length, or, if desired, they may gradually taper or decrease in width and length toward their ends.

The upper edge of the upper section 11 is adapted to be attached in any suitable manner to the upper portion of the car body, preferably the roof structure, and the sides of said upper section are bent rearwardly as designated by 15 for attachment to the corner posts. The body of the upper section 11 is provided with a series of vertically disposed outwardly pressed ribs or corrugations 16 which are counterparts of the ribs or corrugations 14. The lower edge of the upper section 11 is bent outwardly into a horizontal plane to form a flange 17 which lies immediately over the flange 13 on the upper edge of the lower section and interposed between these flanges 13 and 17 is the horizontally disposed leg of a commercially rolled T-bar 18.

Attaching means preferably in the form of rivets 19 are seated in the flanges 13 and 17 and the interposed leg of the bar 18. The flanges 18^a of the bar 18, which occupy a vertical plane, are positioned directly against the inner faces of the sections 10 and 11, and these sections immediately ad-

jacent to the flanges 13 and 17 are bent outwardly or offset as designated by 19^a in order to accommodate the flanges 18^a, and thus the exposed faces of said flanges occupy the same vertical plane with the inner faces 70 of the sections 10 and 11.

In constructing or shaping the upper section 11, the flange 17 is made slightly wider than the flange 13, and this permits the outer edge of said flange 17 to be turned downwardly as designated by 20 to form a protecting flange which overlies the outer end of the bar 18 and the outer end of flange 13. Such construction not only assists in the reinforcement and stiffening of the end, but 80 forms a water and dust shed for the joint between the members 10 and 11, from which the end is formed.

In the construction illustrated in Fig. 5 the flanges 13 and 17 are of equal width and 85 the horizontally disposed leg or web of the T-bar 18 extends beyond the outer ends of said flanges and is bent downward to form a depending flange 20^a which performs the same functions as the depending flange 20. 90

To provide the central portion of the car end with a trussed structure, the flanges 13 and 17 are widened, particularly at their central portions and arranged between the outer portions of said flanges is the horizontally disposed leg or flange of a commercially rolled member 21, such as an angle. Rivets or like fastening devices are seated in the outer portions of the flanges 13 and 17 and the interposed leg or flange 100 of the angle, and the outer leg or flange of said angle depends as shown in Fig. 7, thereby materially reinforcing or stiffening the trussed structure and at the same time forming a water and dust shed. The central portion of the angle 21 is bowed outwardly so as to be spaced apart from the central portion of the T-bar in this structure, and thus the members 18 and 21 perform the functions of trussing elements with 110 the flanges 13 and 17 serving as struts between said elements.

In the construction illustrated in Figs. 8 and 9, the web of a commercially rolled Z-bar 22 is positioned between and riveted 115 to the flanges 13 and 17, with the flange on the inner end of said Z-bar vertically disposed and positioned against the lower edge of the upper section 11. The flange on the outer edge of said Z-bar extends downward to assist in stiffening the trussed structure and to also serve as a water and dust shed. The web of this Z-bar is split lengthwise as shown in Fig. 8, and the outer portion of said split bar is spaced apart from 120 the inner portion, thereby forming tension and compression members of a truss and with the flanges 13 and 17 performing the functions of a strut.

By bending the meeting edges of the sec- 130

tions 10 and 11 outwardly and combining therewith a joint member which is, in some instances, a trussed structure, a transversely disposed reinforcing and strengthening member is provided which, in conjunction with the vertically disposed ribs or corrugations pressed outwardly from the bodies of the sections or panels, materially reinforces and strengthens the entire car end, and as a result, all internally or externally applied shocks or blows and all service strains and vibrations will be transmitted directly to the car underframe and superstructure.

15 The inner face of the car end is perfectly flat and devoid of projections, and therefore, cars equipped with my improved ends are particularly adapted for service in the transportation of explosives.

20 It will be readily understood that minor changes in the size, form and construction of the various parts of my improved car end can be made and substituted for those herein shown and described, without departing 25 from the spirit of my invention, the scope of which is set forth in the appended claims.

I claim:

1. In a car end, a pair of sheet metal sections, the meeting edges of which are bent 30 outwardly to form reinforcing flanges, reinforcing joint members arranged between said flanges and portions of said sections being offset to accommodate said joint members.

2. In a car end, a pair of sheet metal sections, the meeting edges of which are bent 35 outwardly to form reinforcing flanges, reinforcing joint members arranged between said flanges and having portions spaced apart in the direction of load thrusts, and attaching means seated in said flanges and the interposed reinforcing members.

3. In a car end, a pair of duplicate sheet 45 metal sections, the meeting edges of which are bent outwardly to form reinforcing flanges, and a reinforcing joint member arranged between said outwardly bent flanges and forming a water table for the joint.

4. In a car end, a pair of duplicate sheet 50 metal sections provided with corrugations, the meeting edges of which sections are bent outwardly to form reinforcing flanges, and a reinforcing joint member arranged between said outwardly bent flanges and extending at an angle to the corrugations.

5. A car end comprising a pair of duplicate corrugated sheet metal sections, the meeting edges of which are bent outwardly 60 to form reinforcing flanges, and a reinforcing joint member arranged between said outwardly bent flanges and riveted thereto, portions of said sections being offset to accommodate said joint member.

65 6. In a car end, a pair of sheet metal sec-

tions having their meeting edges bent outwardly to form a pair of parallel reinforcing flanges, and a stiffening bar interposed between said flanges and secured thereto and forming a water table for the joint.

70 7. In a car end, a pair of sheet metal sections having their meeting edges bent outwardly to form a pair of parallel reinforcing flanges, compression and tension members interposed between said flanges, and attaching means seated in said flanges and the interposed members.

8. In a car end, a pair of sheet metal sections having their meeting edges bent outward to form parallel reinforcing flanges, 80 and a pair of reinforcing bars interposed between said flanges.

9. In a car end, a pair of sheet metal sections having their meeting edges bent outward to form parallel reinforcing flanges, 85 truss bars interposed between said flanges, and attaching means seated in said flanges and interposed bars.

10. In a car end, a pair of sheet metal sections provided with corrugations and having 90 their juxtaposed edges bent outward to form parallel reinforcing flanges disposed at right angles to the corrugations, and reinforcing joint member secured to said flanges.

95 11. In a car end, a plurality of sheet metal sections having their meeting edges bent outward to form parallel reinforcing flanges, reinforcing members having portions spaced apart from each other interposed between 100 said flanges, and attaching means seated in said parallel flanges and reinforcing members.

12. In a car end, a pair of sheet metal sections, the line of junction of which is displaced horizontally from the plane of the sections, and a trussed reinforcement at the joint between said sections.

105 13. In a car end, a plurality of sheet metal sections having marginal flanges extending 110 from the major plane thereof, fastening means seated in said flanges, and stiffening means coöperating with said flanges to form a transverse trussed reinforcement for said car end, the marginal portions of said sections being offset to accommodate said stiffening means.

115 14. In a car end, a pair of corrugated sheet metal sections provided with marginal flanges, chord members coöperating with the 120 meeting edges of said sections to form a trussed reinforcement for said car end, the said flanges forming a strut member for said chord members.

125 15. A car end comprising a pair of sheet metal sections provided with marginal stiffening flanges, a stiffening member coöperating with the said flanges to form a transverse reinforcement for the end structure, and each section being provided with a 130

series of reinforcing ribs or corrugations terminating at said flanges, said flanges being offset to accommodate said stiffening member.

16. A car end comprising a pair of sheet metal sections having their meeting edges displaced in the line of load thrusts and horizontally disposed, means coöperating with the meeting edges of said sections to form a transversely disposed reinforcement, and each section being provided with a series of outwardly pressed reinforcing ribs or corrugations, which are arranged substantially at right angles to the transversely disposed reinforcement.

17. In a car end, a pair of sheet metal sections, the meeting edges of which are offset in the direction of load thrusts, means coöperating with the meeting edges of said sections and projecting outwardly from the sections to form a transversely disposed reinforcement, and a series of outwardly

pressed vertically disposed ribs or corrugations in each section.

18. In a car end, a pair of sheet metal sections, the meeting edges of which are bent outwardly to form reinforcing flanges, and truss elements interposed between and fixed to said flanges. 25

19. The combination in a car end, of two 30 plates, one located above the other, each plate having a series of corrugations; and a transverse Z-beam wider at the center than at the edges and secured to the two plates, the corrugations of the lower plate being 35 vertical.

In testimony whereof I hereunto affix my signature in the presence of two witnesses, this 22nd day of May, 1914.

JAMES J. COOPER.

Witnesses:

ROBERT J. SCHEIBLI, Jr.,
PAUL M. BEARD.

It is hereby certified that in Letters Patent No. 1,208,916, granted December 19, 1916, upon the application of James J. Cooper, of St. Louis, Missouri, for an improvement in "Railway-Car End Construction," an error appears in the printed specification requiring correction as follows: Page 3, lines 93-94, claim 10, before the word "reinforcing" insert the article *a*; and that the said Letters Patent should be read with this correction therein that the same may conform to the record of the case in the Patent Office.

Signed and sealed this 23d day of January, A. D., 1917.

[SEAL.]

F. W. H. CLAY,
Acting Commissioner of Patents.
